MATTRESS ANCHOR FOR SLEEPING CAR BERTHS

Filed Feb. 23, 1929

UNITED STATES PATENT OFFICE

JOHN F. GAIL, OF EVANSTON, ILLINOIS, ASSIGNOR TO SIMMONS COMPANY, OF NEW YORK, N. Y., A CORPORATION OF DELAWARE

MATTRESS ANCHOR FOR SLEEPING CAR BERTHS

Application filed February 23, 1929. Serial No. 341,979.

This invention relates to an improvement in mattresses for sleeping car berths or the like, and has particular reference to a mattress for the upper berths of Pullman sleeping cars.

The principal object of the invention is to provide means for supporting the mattress in a displaced position to facilitate making up of the berth. Other objects are to provide supporting or anchoring means such as above referred to, which can be readily applied to the standard upper berths of the said sleeping cars, and to provide such means which will not impair the comfort of the berth or otherwise interfere adversely with the usual operations in the manipulation of the said berths.

Other objects and advantages of the invention will be understood by reference to the following specification and accompanying drawing wherein I have illustrated more or less schematically, an upper berth of a Pullman sleeping car and a mattress anchored to the berth in accordance with the principles of my invention.

In the drawing:

Fig. 1 is a plan of an upper berth when the latter is in open position, the mattress being shown displaced to facilitate making up of the berth; and

Fig. 2 is a section on the line 2—2 of Fig. 1.

Referring now to the drawing, I have illustrated a standard upper berth as comprising a main support or tray 5 which is pivotally secured in any suitable manner as shown at 6 to a side wall portion 7 of a sleeping car.

The support or tray 5 is provided with locking bar portions 8 and 9 which extend longitudinally of the berth and are located intermediate the sides thereof, as clearly shown in the drawing. The locking bar parts 8 and 9 are slidably mounted intermediate their ends in bearings 10 and 11 which are secured to the tray or support 5 and the said bars may also be slidably supported in the end walls 12 and 13 of the tray. Control mechanism indicated at 14 is provided intermediate the bearings 10 and 11 for effecting endwise movement of the bars 8 and 9 to lock or unlock the tray when in closed position. The

above described berth structure is illustrative of the standard upper berth construction and is sufficient for the purpose of illustrating the present invention.

According to the usual custom, mattresses are provided which fit in the support or tray 5, these mattresses being loose or unattached to the tray so that the mattresses may be displaced by the attendant of the car to facilitate making up of the berth.

The usual procedure in making up the berth has been for the attendant to stand on a ladder and then to lift the mattress over the outer edge of the tray and to support the mattress on the edge of the tray. To prevent the mattress from falling to the floor, it has been necessary for the attendant to hold the mattress up in any possible manner, this often being done by leaning against the mattress to firmly press the same against the outer edge of the tray or in any other manner whereby the attendant's hands and arms are left free to handle the bedding. While so supporting the mattress, the attendant throws the bedding partly over the inner edge of the mattress, which at that time is disposed in a more or less vertical position. When the bedding is positioned to the satisfaction of the attendant, the mattress is pushed back into place in the tray and the outer edge of the bedding tucked between the outer edge of the mattress and the outer portion of the tray. This procedure has been found to be difficult, awkward, and to require more time than it is desired to spend in making up the berths.

For overcoming the above indicated difficulty, I provide a mattress 15 substantially of the usual construction which fits the tray 5. An anchor member 16, preferably of flexible textile material, such as canvas or other suitable fabric, is secured adjacent one of its edges by means of stitching or otherwise, as indicated at 17, to the bottom of the mattress. I have found it desirable to secure the anchor 16 to the bottom of the mattress along a line extending longitudinally thereof and located intermediate the sides of the mattress, somewhat nearer to the outer edge of the mattress than to the inner edge.

The opposite edge of the anchor 16 is provided with flap portions 17a, 18, 19 and 20, which are formed by cutting out portions as indicated at 21, 22 and 23, so that the flaps will fit between the locking bar control mechanism 14 and the adjacent bearings 10 and 11 and between the bearings 10 and 11 and the respectively adjacent end walls 12 and 13 of the tray. The flap portions of the anchor are adapted to be looped around the locking bars, as clearly shown in Fig. 2, and snap fasteners 24 of a well known construction are provided for detachably or disengageably securing the flaps so looped around the said locking bars.

By an inspection of Fig. 2, it will be understood that the anchor member 16 is operative to support the mattress in approximately vertical position on the outer edge or side of the tray 5. As shown in Fig. 2, a portion 20 of the mattress spaced below the line of stitching uniting the anchor to the bottom of the mattress engages the lower corner portion of the tray, as indicated at 25 and the anchor 16 prevents the mattress from swinging about the corner portion 25 as a fulcrum, and also prevents the mattress falling to the floor. The arrangement is preferably such that the mattress will incline outwardly and upwardly slightly, as shown in the drawing, so that 25 gravity will tend to swing the mattress outwardly and will thus prevent the mattress from accidentally falling back into the tray. It is not, of course, necessary that the anchor be effective to maintain the mattress in the above described upwardly extending position. In some instances, possibly due to variations in the dimensions of the anchor member or other parts, the mattress may assume 30 an outwardly displaced position more or less horizontal or even inclined downwardly. The principal object of the invention is nevertheless accomplished, since the attendant of the car is relieved of the necessity of holding 35 the mattress while making up the berth.

When the mattress is supported in overhanging or displaced position, as shown in Fig. 2, the attendant of the car may work with the greatest facility in making up the berth. The usual bedding may be thrown 40 over the upper or inner edge of the mattress, as indicated in Fig. 2, after which the mattress may be swung back into the tray and the outer marginal portions of the bedding tucked into the desired position.

I am aware that changes may be made in the above described mattress supporting or anchoring structure without departing from the spirit of the invention, the scope of which 45 should be determined by reference to the following claims, the same being construed as broadly as possible consistent with the state of the art.

I claim as my invention:

65 1. In combination with a sleeping car berth

or the like and a mattress therefor, a flexible anchor member extending between and secured at its opposite ends respectively to the bottom of said mattress and to a part of said berth, the mattress end of said anchor being 70 secured to the bottom of the mattress at a point located intermediate the sides of the mattress but nearer to the outer side thereof than to the inner side, said anchor member being arranged to permit limited displacement of the mattress from the berth and to support the mattress in a displaced position for facilitating making up of the berth.

2. In combination with a sleeping car berth or the like and a mattress therefor, an anchor member comprising a flexible member of textile material extending lengthwise of said mattress and secured adjacent one edge to the mattress, and detachably secured adjacent its other edge to a part of said berth, the width 80 of said anchor member being such as to permit limited displacement of the mattress and also such that the anchor member is operative to support the mattress in partially displaced position for facilitating making up of the 85 berth.

3. In combination with a sleeping car berth or the like and a mattress therefor, an anchor member comprising a flexible member of textile material extending lengthwise 90 of said mattress and secured adjacent one of its edges to the bottom of the mattress intermediate the sides of the latter, and detachably secured adjacent its opposite edge to a part of said berth located intermediate the 95 sides of the latter, the width of said anchor member being such as to permit limited displacement of the mattress and also such that the anchor member is operative to support the mattress in partially displaced position 100 for facilitating making up of the berth.

4. In combination, a sleeping car upper berth or the like comprising a mattress support, a locking bar disposed on the inside of said support and extending longitudinally 110 thereof, a mattress fitting said support, and an anchor member comprising a flexible member of textile material extending lengthwise of the mattress and united adjacent one of its edges to the bottom of said mattress 115 along a line disposed intermediate the sides of the mattress, the opposite marginal portion of said anchor member being adapted to be looped around said locking bar, and said portion being provided with disengageable fasteners for maintaining said part so looped around said bar, the width of said anchor member being such as to permit limited displacement of the mattress and also such that the anchor member is operative 120 to support the mattress in partially displaced position for facilitating making up of the berth.

5. In combination, a sleeping car upper berth or the like comprising a mattress sup- 125

port, a locking bar disposed on the inside of said support, extending longitudinally thereof intermediate its sides and slidably mounted on said support by means of spaced bearings secured to the support intermediate the ends thereof, and control mechanism disposed inside of said support intermediate said bearing members, a mattress fitting said support, and an anchor for preventing complete displacement of said mattress from said support, said anchor comprising a textile material member extending longitudinally of said mattress, united adjacent one of its edges to the bottom of the said mattress intermediate the sides of the latter, and provided adjacent its opposite edge with a plurality of flap portions adapted to be looped around said locking bar, said flaps fitting between said control mechanism and bearings and between said bearings and the ends of said support, and being provided with disengageable means for maintaining said flaps so looped around said bar.

JOHN F. GAIL.
